UNITED STATES PATENT OFFICE.

JAMES S. SMITH, OF NEW YORK, N. Y.

MILITARY CAP.

Specification of Letters Patent No. 29,724, dated August 21, 1860.

To all whom it may concern:

Be it known that I, JAMES S. SMITH, of the city, county, and State of New York, have invented certain new and useful Improvements in Military Caps, &c.; and I do hereby declare that the following is a full, clear, and exact description of the same, reference being had to the accompanying drawing, forming a part of this specification, in 10 which—

Figure 1 represents a vertical central section of my invention. Fig. 2 is a plan or top view of my ventilator. Fig. 3 is a transverse vertical section of the same. Fig. 4 is 15 an inverted plan of the same.

Similar letters of reference in all the figures indicate corresponding parts.

The object of this invention is to arrange the ventilating channels and openings in 20 such a manner that the same allow a free circulation of the air and that they exclude the rain and my invention consists, first, in arranging in the upper part of a hat or cap an annular channel with inclined sides, 25 which communicates with the interior of the cap or hat and with the external atmosphere through a series of apertures, in such a manner, that the foul air from the interior of the cap or hat is allowed to pass freely out 30 into the external air without allowing any water or rain to enter; second, in combining with said annular channel a false bottom with a series of perforations in such a manner that an air chamber is formed in the 35 top of the cap or hat, and that the force of the sun's rays, as the same strike the crown of the hat or cap, is broken before the same can have any injurious influence on the head of the wearer of the cap; third, in arranging 40 the usual circular perforated ventilators with an annular lip or flange under the ventilating holes in such a manner, that the water which may enter through these holes is shut off from the interior of the cap or hat 45 and caused to pass out through these holes on the opposite side.

To enable those skilled in the art to make and use my invention, I will proceed to describe it with reference to the drawing.

50 The form of the cap A, which I have represented in Fig. 1 of the drawing, is that of an ordinary military cap, but it must be remarked that I do not confine myself to this sort of caps only. My improvements 55 can be applied to all sorts of hats or caps with equal advantage.

The crown of the cap A is provided with a channel *a*, which passes all the way around and which is furnished with a series of perforations *b*, constituting a communication between said channel and the interior of the cap. The sides of this channel are inclined and it is covered over by the tip B, which is fastened to the body of the cap, in the usual manner. This tip is provided with apertures *c*, which form a communication between the channel *a* and the external atmosphere. By these means the foul air from the interior of the cap is allowed to pass freely out, and at the same 60 time if it rains, the water which may enter through one of the apertures *c* flows down over the inclined sides of the channel *a*, without being allowed to enter into the interior of the cap. A false bottom D, is 65 placed in the inside of the cap, resting against the sides of the channel *a*, and forming an air chamber, which communicates through openings *g*, in the bottom D with the interior of the cap. This air chamber 70 serves to counteract the injurious influence of the sun's rays, as they strike the tip of the cap.

In the front of the cap I have applied one of my brass ventilators C, which consist of 75 a circular plate *d*, raised in the center and provided with a series of prongs *e*, that serve to fasten the ventilator to the cap. With ordinary ventilators of this kind the openings *f* are in direct communication with 80 the interior of the cap and if it rains the water runs freely down into said openings and over the face of the wearer. To prevent this I have arranged a circular flange or lip *h*, under the openings *f*, and bent up 85 as clearly shown in Figs. 1 and 3, so that the water which may flow in through one of the openings *f*, in the upper side of the ventilator is conducted down to the openings 90 on the opposite side and no chance is given 95 to said water to enter the interior of the cap.

This ventilator may be applied with advantage to all sorts of hats and caps and it can be used either in a vertical position as shown in the drawing or in a horizontal 100 position in the tip of a cap or hat if it is desirable.

Having thus fully described my invention, what I claim as new, and desire to secure by Letters Patent, is—

110 1. The arrangement of the annular channel *a* in combination with the tip B, of a

cap or hat, constructed and operating substantially as and for the purpose set forth.

2. The combination with the annular channel a , of a perforated false bottom D , substantially as and for the purpose specified.

3. The arrangement of the annular flange

or lip h , in combination with the ordinary ventilator C , constructed and operating substantially as and for the purpose described. 10

JAMES S. SMITH.
